SLIPPER SOCK

Harold E. Clayton, Jr., 2 Fairbanks Road,
Chelmsford, Mass. 01824

Filed Feb. 2, 1967, Ser. No. 5,666

Term of patent 14 years

(Cl. D2—266)

Fig. 1.

Fig. 2.

Fig. 3

Fig. 4.

FIG. 1 is a top perspective view of a slipper sock showing my new design, the partially shown ornamental knit is continuous as indicated by the broken lines;

FIG. 2 is a side elevational view thereof, the slipper sock being in a relaxed position;

FIG. 3 is a bottom plan view, and

FIG. 4 is a top plan view of the slipper sock as it appears with the heel portion inserted into the toe portion.

I claim:

The ornamental design for a slipper sock, as shown and described.
